UNITED STATES PATENT OFFICE.

JOHN H. CODRICK, OF PHILADELPHIA, PENNSYLVANIA.

NOZZLE FOR VACUUM CLEANERS.

Application filed March 29, 1927. Serial No. 179,245.

My invention relates to vacuum cleaners and more particularly to an improved nozzle for such machines.

In operating a vacuum cleaner, it is necessary that the suction nozzle be disposed approximately in contact with the surface to be cleaned in order to obtain the maximum efficiency of the machine. This requirement is usually very difficult to meet due to inequalities in the surfaces being cleaned and difficulties in making proper adjustments in the height of the nozzle from the floor.

It has long been recognized that a rotatable nozzle which will actually make contact with the floor would possess great advantages over the conventional types of nozzles, and the principal object of my invention is to provide such a rotatable nozzle.

Vacuum cleaners are ordinarily supported on wheels disposed at both the front and back of the body structure, and another object of my invention is to so design the rotatable nozzle that it may be substituted for the front wheels, when it is so desired, and in this manner assure that the nozzle is firmly pressed against the surface to be cleaned.

Still another object of my invention is to provide a nozzle which may be used in a vacuum cleaner by itself, in combination with a brush or other nozzles, or in any other combination that may be desired.

These objects, and other advantageous ends which will be described hereinafter, I attain in the following manner, reference being had to the accompanying drawings in which—

Figure 1 shows a vacuum cleaner in which a preferred embodiment of my invention has been mounted in combination with an ordinary rotatable cleaning brush; a portion of the nozzle casing being broken away and the brush and nozzle shown in section in order to illustrate the relation of my invention to the other parts of the vacuum cleaner.

Figure 2 is an elevation of a preferred form of a rotatable nozzle, partly in section,

Figure 3 a section on line 3—3 on Figure 2, and

Figure 4 a top plan view of the axle forming a part of my invention.

Referring now more in detail to the drawings, the nozzle is provided with an axle 5 having a slot 6 extending nearly its entire length but leaving solid portions 7 at each end on which disks 8 are rotatably mounted. Reduced portions 9 are formed on each end of shaft 5 and adapted to be secured in the

nozzle casing 10 of a vacuum cleaner 11 and held against rotation in any suitable manner.

Radially disposed vanes 12 are rigidly secured between disks 8 and held in spaced relation to one another so as to form a wheel 13; the space between the inner edges of adjacent vanes being slightly greater than the width of slot 6 and the vanes so disposed that the space between each two adjacent vanes is diametrically opposed to a similar space between two other adjacent vanes. Axle 5 is preferably made of steel and polished, while wheel 13 is made of different material so as to reduce the friction between it and axle 5 to a minimum. It is evident that, as the wheel 13 rotates on shaft 5, the openings between the lowermost vanes and between the uppermost vanes 12 will align with slot 6 and form a free passage therethrough so that if suction is applied to the uppermost pair of vanes, the full effect of such suction will be transmitted to the surface disposed between the lowermost pair.

In adapting the device to different types of cleaners, different mountings must be employed but it is necessary that the rotatable nozzle be mounted in a housing which will prevent any great quantity of air from passing between the interior of the housing and the outer edges of vanes 12 and, for the purpose of illustration, I have shown the nozzle mounted in a vacuum cleaner in combination with an ordinary rotatable brush. In this instance, I have provided a nozzle housing with a back wall 14 and a partition 15 which are curved to conform to the shape and size of the nozzle so that the nozzle may rotate in this housing with as little clearance as possible between the outer edges of vanes 12 and the interior walls of the housing; the upper portions of back wall 14 and partition 15 forming a continuation of the air passage in nozzle casing 10. The mechanism and mode of operation of vacuum cleaner 11 has not been illustrated and described as it is well known in the art and nearly all of the present types of vacuum cleaners may be adapted to use my improved nozzle.

In operation, the brush is rotated in any desired manner and tends to loosen the dirt in the carpet or rug and to move it toward wheel 13 which will draw such dirt into vacuum cleaner 11 as its successive pairs of vanes come in registry with slot 6. It is evident that by pressing the two lowermost vanes against the surface to be cleaned, the full force of the suction fan in the vacuum cleaner

is applied to the limited area between such two vanes, with the result that a more thorough cleaning can be given the surface than is now possible with the same amount of power.

While I have described my invention as taking a particular form, it will be understood that modifications may be made without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a vacuum cleaner, a casing, a horizontal axle mounted therein, having a substantially vertical longitudinal slot extending therethrough, a disk on each end of the axle, members extending between the disks closely fitting the axle and adapted to engage the surface to be cleaned, a nozzle having its front and rear walls curved about the axis of the axle, and closely embracing the members extending between the disks.

2. In a vacuum cleaner, a casing, a hori-

zontal axle mounted therein, having a substantially vertical longitudinal slot extending therethrough, a disk on each end of the axle, circumferentially spaced vanes extending between the disks adapted to engage the surface to be cleaned and having their inner edges in close proximity to the axle, and a nozzle having its front and rear walls curved about the axis of the axle, and closely embracing the outer edges of the vanes.

3. In a vacuum cleaner, a casing, a horizontal axle mounted therein, having a substantially vertical longitudinal slot extending therethrough, a disk on each end of the axle, oppositely disposed vanes extending between the disks adapted to engage the surface to be cleaned and having their inner edges in close proximity to the axle, and a nozzle having its front and rear walls curved about the axis of the axle and closely embracing the outer edges of the vanes, whereby the oppositely disposed passages between the vanes will consecutively communicate with the slot in the axle and consequently with the nozzle.

In testimony whereof I have signed my name to this specification.

JOHN H. CODRICK
